(57) **CLAIM**

The ornamental design for an exterior display for a vehicle pillar as shown and described.

DESCRIPTION

FIG. 1 is a front perspective view of an exterior display for a vehicle pillar of the present disclosure;
 FIG. 2 is a rear perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof.
 The broken lines depict portions of the exterior display for a vehicle pillar that form no part of the claimed design.
